UNITED STATES PATENT OFFICE.

HENRY GRIESER, OF ST. LOUIS, MISSOURI, ASSIGNOR OF TWO-THIRDS TO
CHARLES L. HOOD AND CHARLES B. TOMLINSON, OF SAME PLACE.

STREET-CAR FENDER.

SPECIFICATION forming part of Letters Patent No. 529,726, dated November 27, 1894.

Application filed April 4, 1894. Serial No. 506,239. (No model.)

To all whom it may concern:

Be it known that I, HENRY GRIESER, of the city of St. Louis and State of Missouri, have invented certain new and useful Improvements in Street-Car Fenders, of which the following is a full, clear, and exact description, reference being had to the accompanying drawings, forming a part hereof.

The object of this invention is to provide improved means for preventing a person, or living object, from being caught beneath a moving car.

This invention consists in the combination of a plurality of angle-arms fulcrumed to the car, and an apron hinged to said angle-arms, and supplementally connected to the car, together with yielding pressure devices interposed between the apron and its support, whereby said apron may normally be held in a given position, subject to a depression upon the application thereto of a sufficient weight.

My invention consists further in the arrangement, combination and construction of parts hereinafter set forth, pointed out in my claims, and illustrated by the accompanying drawings, in which—

Figure 1 is a side elevation, showing my device applied to a car in position for practical use. Fig. 2 is a plan view of Fig. 1 detached from a car. Fig. 3 is a side elevation, showing my device attached to a car, as required for practical use, the dotted lines indicating two additional positions of the device. Fig. 4 is a perspective view of one portion of a buffer-plate. Fig. 5 represents perspective views of the supporting plates. Fig. 6 is an enlarged detail sectional view, illustrating the manner of supplementally attaching the apron to the car. Fig. 7 is a perspective view of a ratchet-bar.

In the construction of the device as shown, the numeral 10 designates a car platform, to which is attached, and from which depend, two angle-plates 11, 12 (Fig. 5), identically formed angle-plates being provided at opposite sides of the platform. Located between the angle-plates 11, 12, and pivoted thereto, and extending forwardly therefrom, are angle-arms 13. The angle-arms 13 also extend rearwardly from the point of fulcruming thereof, and the rear end portions thereof are

bent upwardly, and extended to a plane of contact with the car platform. An apron is hinged to the forward end portions of the angle-arms 13, which said apron comprises vertically curved side-bars 14, 15 connected at their forward ends by a buffer-plate 16, and at their rear and upper ends by a tie-rod 17, the side-bars 14, 15 being attached to the hinges 18, which form the connection with the angle-arms 13.

Fixed to the lower face of, and extending forwardly from, the buffer-plate 16, is a plate 19, made of rubber, or other yielding, compressible, elastic material, adapted to be carried in the plane of thrust of the car, and receive the impact of the resisting body.

Fixed to the angle-arms 13, 13, and interposed between said angle-arms, and the side-bars 14, 15 of the apron, are leaf-springs 20, 20, which said leaf springs compose yielding pressure devices adapted to retain the apron in a normal inclined plane, preparatory to the application thereto of a moving force.

Fixed to the rear edge of the buffer-plate 16, and to eyes located in the forward end portions of the side-bars 14, 15, is one side of a meshed net 21, the opposite side of said net being secured to the tie-rod 17, the mid-portions of said net being stayed to the side-bars 14, 15 by guy ropes, or stay cords 22, 23. Fulcrumed upon the outer surface of the side-bar 15, of the apron, is a ratchet-bar 24, the free end portion of which ratchet-bar extends through a slot 25 in the forward portion of the angle-plate 11.

That portion of the angle-plate 11, forming the lower side of the slot 25, is bent inwardly and attenuated at its extreme edge, the attenuated edge thereof being adapted for engagement with the ratchet teeth on the bar 24.

Fixed to the side-bar 14, at a point approximately horizontally opposite to the point of attachment of the ratchet-bar 24, is a chain 26, the opposite end of which chain is attached to a screw-eye, or staple located in the forward portion of the angle-plate 12 on the side of the car immediately in the rear of the side-bar 14.

When it is desired not to employ the fender, the chain 26 is detached from the side-bar 14, and the ratchet-bar 24 is withdrawn from the

slot 25 in the angle-plate 11, and the entire device elevated, as shown by dotted lines 27 in Fig. 3; but when it is desired to employ the fender, it normally remains in the position shown in Figs. 1 and 3, occupying an inclined plane, the buffer-plate being in a plane below the angle-arms 13.

If, during the advance of a car, the rubber-plate 19, carried upon the buffer-plate 16, contacts with a resisting body, such as a person, said rubber plate will yield and cushion the force of the impact with said body. By reason of the force of the impact, the aforesaid body will be precipitated upon the meshed net 21 at a point in the rear of the hinges 18, and, by reason of its weight, will depress the said net, and the side-bars carrying the same, thus compressing the yielding devices interposed between the apron and its support, and longitudinally moving the ratchet-bar 24 within the slot 25, such movement being determined and limited by the relative resistance of the yielding pressure devices to the weight applied upon the apron, thus cushioning the fall of the body upon the apron, and minimizing the possibility of injury thereto.

Reaction of the apron, through the resilience of the yielding pressure devices, is obviated and prevented by the engagement of the teeth on the ratchet-bar 24 with the lip formed on one side of the slot 25, thus providing for the retention of a moving body upon the apron, until such time as the car, on which the apron is carried, may be stopped.

It is obvious that upon the removal of a person, or object, alighting upon the apron, said apron may be repositioned through the

resilience of the yielding pressure devices, by the disengagement of the ratchet-bar from the aforesaid lip of the angle-plate 11.

40

What I claim is—

1. In a car fender, the combination of angle-plates fixed to, and extending downwardly from, a car platform, angle-arms fulcrumed in said angle-plates, an apron hinged to the forward ends of said angle-arms, yielding pressure devices interposed between said angle-arms and apron, a ratchet-bar pivotally connected to said apron and adapted for engagement with one of said angle-plates, and a chain fixed to said apron and adapted for attachment to one of the remaining said angle-plates.

2. In a device of the class described, a plurality of angle-plates arranged in pairs and fixed to, and depending from, a car platform, angle-arms fulcrumed within the respective pairs of angle-plates, an apron hinged upon the forward end portions of the angle-arms, leaf springs interposed between the angle-arms and the apron, a ratchet-bar fulcrumed on the apron and extended through a slot in one of said angle-plates and adapted for engagement with said angle-plate, and a chain fixed to one of the remaining angle-plates and adapted for detachable connection with the said apron.

In testimony whereof I affix my signature in presence of two witnesses.

HENRY GRIESER.
